UNITED STATES PATENT OFFICE.

MOSES LA LONDE, OF INDIAN ORCHARD, MASSACHUSETTS, ASSIGNOR OF ONE-HALF TO JOHN W. SUPERNEAW AND ONE-FOURTH TO ELZEAR PATENAUDE, BOTH OF SPRINGFIELD, MASSACHUSETTS.

DOOR CHECK AND STOP.

No. 820,581.

Specification of Letters Patent.

Patented May 15, 1906.

Application filed July 31, 1905. Serial No. 271,878.

To all whom it may concern:

Be it known that I, MOSES LA LONDE, a British subject, and a resident of Indian Orchard, in the county of Hampden and State of Massachusetts, have invented certain new and useful Improvements in Door Checks and Stops, of which the following is a full, clear, and exact description.

This invention relates to improvements in door-checks of a kind which are entirely mechanical in character and which may serve both as a yielding resistance or check against the movements of the door and as a stop for positively confining the door, when desired, in any fully or partially opened position.

The objects of the invention are to provide an appliance for the purpose indicated which is very simple and inexpensive of construction, having little liability to derangement after protracted use and having entire efficiency both as a check and a stop, with susceptibility for variation of the yielding pressure against which the door swings.

The invention consists in a device having parts in combination and of construction as hereinafter fully and clearly described in conjunction with the accompanying drawings, and as set forth in the claims.

In the drawings, Figure 1 is a perspective view showing the check as applied in relation to a door jamb or casing and a door. Fig. 2 is a perspective view showing in separated relations the more important portions of the device; and Fig. 3 is a sectional view as taken on line 3-3, showing in properly-assembled relations for action the same parts as are included in Fig. 2.

Similar characters of reference indicate corresponding parts in all of the views.

In the drawings, A and B represent members for attachment, respectively, to a door-jamb and to a door, or vice versa. The member A comprises a back or attachment plate 10, having the forwardly-extending lug 12, made with a vertical socket 13, in which the downwardly-turned member 14 of the horizontal rod C has a pivotal or swiveling engagement, whereby the rod may freely swing in a horizontal plane. The member B, here shown as attached on the side of the door, comprises the back or attachment plate 16 and the forwardly-extending lug 17, having the horizontal perforation 18 therethrough, through

which said rod C has a guiding engagement, and said lug having the upstanding screw-stud 19.

D represents a saddle or yoke-shaped shoe having through its middle or arch portion the vertical aperture 22, by which provision the shoe is engaged about the screw-stud 19, while its opposite horizontally-extending bearing members or shoes 23, longitudinally grooved at their under sides, as seen at 24, not only frictionally bear on the upper side of the rod, but so engage the latter as to be prevented from any revoluble displacing movement.

A spiral spring 25 encircles the screw-stud, having its lower end resting on the top of the saddle-shoe, while the top of this spring is borne against by the thumb-nut 9, which screw engages on the upper extremity of the stud 19.

As particularly shown in Figs. 2 and 3, the nut is constructed with the downwardly-opening recess 30, such cup-shaped lower portion of the nut enveloping and giving space for occupancy therewithin of the spring.

Manifestly by loosening the nut tension on the spring and the friction between the shoe members 23 and the rod may be very slight, so that the door may be swung without any material resistance to its movements. By turning the thumb-nut downward in a moderate extent the frictional engagement between the saddle-shoes and rod will become such as to constitute an adequate check, with possibility for positively moving the door to any position desired and with the assurance that the door will remain where placed, and again, by turning the nut sufficiently far downward the limits for compression of the spring may be exceeded and the saddle-shoe may be forced with such a hard bind against the rod as to prevent any movement of the rod relatively to the shoe, even were the door to be quite forcibly pushed, so that under the latter-described condition the device becomes a stop.

The arrangement and connection of the parts of this appliance in relation to the jamb and door are preferably as illustrated in the drawings, although manifestly a reversal of the arrangement could be made in an entirely operative manner—that is, the member or fitting A might be attached on the door

and the parts B, d, and g might be located at or near the jamb.

Having thus described my invention, what I claim, and desire to secure by Letters Patent, is—

1. In a door-check, members for attachment respectively to a door-jamb and to a door, a rod, swiveled to one of said members to swing in a horizontal plane, and having a guiding engagement horizontally through the other member, and a friction device associated with the member relatively to which the rod is guided, comprising a saddle-shaped shoe having opposite rod-bearing members, a spring for pressing the shoe against the rod and a nut-screw engaging an extension of the rod-engaging member and coacting with said spring.
2. In an appliance of the character described, in combination, members for attachment to a door and a door-jamb, a rod pivotally connected to one of said members, and the

other of said members having a perforation for the engagement of the rod horizontally therethrough, and provided with an angularly-extending screw-stud, a saddle or yoke-shaped shoe, intermediately vertically apertured, engaging about said screw-stud having the opposite members thereof grooved at their under side, and in frictional bearing against the rod at opposite sides of said perforated member, a spiral spring encircling the screw-stud and reacting downwardly against the saddle-shoe, and a nut engaging the screw-stud, and for tensioning the spring, and constructed with a cup-shaped downwardly-open lower portion for enveloping the spring.

Signed by me at Springfield, Massachusetts, in presence of two subscribing witnesses.

MOSES LA LONDE.
